UNITED STATES PATENT OFFICE.

JOHN L. VIDAR, OF LOS ANGELES, CALIFORNIA.

COMPRESSOR FOR AMMONIA SYSTEMS.

1,120,635.

Specification of Letters Patent.

Patented Dec. 8, 1914.

Application filed April 3, 1912. Serial No. 688,305.

To all whom it may concern:

Be it known that I, JOHN L. VIDAR, a citizen of the United States, residing at Los Angeles, in the county of Los Angeles and 5 State of California, have invented new and useful Improvements in Compressors for Ammonia Systems, of which the following is a specification.

This invention relates to improvements in 10 compressors and particularly to that class of compressors that are adapted for use in ammonia cooling systems.

It is an object of the invention to provide a compressor for anhydrous or other 15 ammonia, or fluids of any kind in which the valves employed will seat perfectly at all times for preventing the return of the material after it is compressed, the valves being mounted in a casing having no portions 20 constructed so as to facilitate leakage.

It is also an object of the invention to provide a fluid compressor having a casing provided with removable valve seats formed with depressed seats and having spring 25 actuated balls adapted to engage the same.

It is also an object of the invention to provide a fluid compressor especially adapted for the compressing of ammonia in which inner and outer casings are provided, 30 and in which valve mechanisms are located in the walls between the casing, facilitating the handling of ammonia without the danger of leakage.

It is a still further object of the invention 35 to provide a compressor formed with a water jacketed cylinder and having bores extending into the same to receive valve mechanisms, and to provide removable valve seats which may be positioned in said bores, 40 ball valves being employed in connection therewith.

In the accompanying drawing forming a 45 part of this specification, Figure 1 is a central longitudinal sectional view taken through the improved compressor. Fig. 2 is a transverse sectional view taken upon the line 2—2 of Fig. 1. Fig. 3 is a transverse sectional view taken upon the line 3—3 of Fig. 1. Fig. 4 is an enlarged detail sectional view through one of the valve seats removed from the casing of the compressor. 50

The details and features of the invention will now be more particularly described, reference being had to the said drawing in 55 which—

5 indicates an inner casing forming a

cylinder in which is movably mounted a compressor piston 6. The piston is provided with a piston rod 7, adapted to extend to any suitable mechanism, whereby it 60 may be reciprocated for pumping and compressing ammonia or other fluids. Outside the casing 5 is an outer casing 8 having a sufficient space left between it and the said casing 5, to form a water jacket of proper 65 size. The end of said casing 8 is adapted to be opened, being provided with a removable cap plate 9, which is secured in position by bolts 10. The head of the cylinder 5 is preferably made quite thick and is connected by portions 11 and 12 with the walls of the outer casing 8. The said head and the connections referred to, afford material in which recesses may be formed to receive suitable valve mechanisms. The said head 70 is provided with a bore 13 extending into the same, parallel with the piston rod 7, and the said bore is made to pass entirely through the head of the cylinder, the inner end thereof being somewhat reduced in diameter and threaded at 14, to receive a removable valve seat 15. The outer end of the 75 said bore is also screw threaded and adapted to receive a plug 16. A ball valve 17 is mounted in the passage 13 and a spring 18 is interposed between the same and the plug 16, normally tending to hold the valve to its seat. Entering the valve passage 13 from the side is a bore 19 formed in the 80 connecting portion 12 of the casing. An outlet pipe 20 is fitted into the end of said bore 19 and leads the compressed ammonia to any desired point. The casing portion 11 is also provided with a passage 21 similar to the passage 13 and bored into the material from the end of the casing. The inner 85 end of said passage is provided with a reduced screw threaded portion 22 in which a valve seat 23 is mounted, and screw plug 24 closes the outer end of said passage 21. A ball valve 25 is mounted in the passage 21 and a spring 26 normally holds it to its seat. An angular bored passage 27 is also formed in the end of the cylinder leading from the 90 passage 21 into the interior of the cylinder 5. It will thus be seen that both passages which enter the cylinder 5, enter through the end wall thereof so that the piston may travel approximately the full length of the cylinder in its operation. A passage 28 is 95 formed in the portion 11 of the casing and communicates with the passage 21, the outer

end of said passage having an inlet pipe 29 fitted therein. The water jacket space is provided with an inlet pipe 30 and an outlet pipe 31 to facilitate the proper circulation of cooling water through the said jacket.

Both of the valve seats 15 and 23 are preferably made as illustrated in Fig. 4 in which the said valve seats are shown with a 10 central bore 32 having a dish shaped valve seat portion 33 at one end, to properly receive the ball valves. The said valve seat is formed with holes 34 drilled in from the outer face thereof, to receive a suitable instrument or wrench whereby the seat may 15 be turned into and out of place.

The compressor is found in practice to be especially well adapted for the pumping and compressing of ammonia in cooling systems, the movement of the piston away from the head of the cylinders operating to draw in ammonia past the valve 25, the valve 15 being seated for preventing a return in of ammonia previously pumped into the outlet pipe. The return stroke of the piston forces the ammonia drawn into the cylinder past the valve 15 and to any desired point in the system, the valve 25 being seated during the time.

30 Heretofore valves employed in compressing devices, and particularly ammonia compressors, have shown a tendency to become readily clogged so that they do not work well, especially when foreign materials or 35 flakes lodge between the valves and their seats. This trouble is obviated and entirely prevented in the present device by the employment of the peculiarly formed valve seats described and the spring pressed balls.

40 The continual moving of the balls back and forth against the seats is found to more or

less cause the rotation or twisting thereof under the action of the springs, so that foreign particles do not collect or remain upon the valve seats. The shape of the valve seats 45 moreover prevents the necessity for regrinding the valves and the parts wear a great length of time. It will be observed also that all the moving parts are so mounted within the casing, that there is practically no 50 chance for leakage of the ammonia or other material being compressed, at any point.

What I claim is:

In a compressor, a cylinder, an outer casing surrounding the cylinder, a head closing 55 one end of the cylinder and connecting with the inner walls of the outer casing, said cylinder casing and head being formed integral, said head formed with a pair of bores therethrough, one bore leading to one 60 side of the cylinder and connecting at its end with an inlet opening in the outer casing and communicating at its ends with the interior of the cylinder, the other bore communicating at its inner end with the interior of the cylinder and connecting intermediate its ends with the outlet opening in the outer casing, said bores reduced in diameter at their inner ends, valve seats 65 threaded in the reduced inner ends of the 70 bores, ball valves mounted on said seats within the bores, plugs threaded in the outer ends of the bores closing same, and springs interposed between the plugs and ball valves.

In witness that I claim the foregoing I 75 have hereunto subscribed my name this 26th day of March, 1912.

JOHN L. VIDAR.
